UNITED STATES PATENT OFFICE.

RUDOLF PIETER VAN ALPHEN, OF THE HAGUE, NETHERLANDS.

APPARATUS FOR ONWARD MOVEMENT IN SWIMMING ATTITUDE IN THE WATER.

Application filed April 11, 1927, Serial No. 182,936, and in the Netherlands March 30, 1926.

The invention relates to an apparatus for onward movement in swimming attitude in the water by the aid of a propelling device to be driven by the feet.

5 The invention contemplates simplification of devices of this character by arranging various parts as floating members to obtain an efficient distribution of the floating power and to avoid use of separate floats.
10 These advantages are obtained according to the present invention by using a vertical floating plane and two horizontal floating planes arranged on the upper edges of the same, one of which serves for supporting the
15 upper part of the body, the other extending above the feet.

To these floating planes the propelling and steering devices as well as means for further support for the body are arranged.
20 The drawing discloses a side view of an apparatus constructed in accordance with the invention.

The apparatus comprises a flat body, consisting of two parts 1 and 2 preferably floating vertically on the water. The one part is slidably attached to the other and can be adjustably positioned by the aid of a screw with winged nut 3.

25 The foremost part 1 is provided with a support 4 with bent upper surface on which the body of the swimmer rests, and with a support 5 for the chin. At the front a vertical shaft 6 is arranged rotatably, carrying below the part 1 a rudder blade 7, the top being provided with a crossbar 8 which is within the reach of the hands and therefore may serve for turning the rudder.

In the back part 2 a propeller shaft 9 with propeller 10 is rotatably arranged. The propeller shaft 9 is connected by a bevel gear 40 11, 12 with a cross shaft on which cranks 13 with pedals 14 are positioned. These pedals are within reach of the feet of the swimmer, so that the propeller can be driven by the
45 same.

At the top of the part 2 a plane 15 is arranged which during movement of the apparatus in the water prevents this part from being drawn downwardly.

The support 4 and the plane 15 are preferably constructed so that they supply the necessary buoyancy for the apparatus.

I claim:

In a device of the character described, two longitudinally adjustable vertical sections of small width in comparison to their height, a substantially flat horizontal buoyant section on one of said vertical sections for supporting the body portion of a swimmer, a substantially flat horizontal buoyant section on the second vertical section, a propeller mounted in the rear end of said second vertical section, manually operable means for rotating said propeller to cause movement of said device, and a manually controlled rudder adjacent the front end of said first vertical section, the longitudinal adjustment of said vertical sections permitting adjustment to the requirements of the individual swimmer.

In testimony whereof I affix my signature.

RUDOLF PIETER VAN ALPHEN.
